HEEL OPERATED DRUM BEATER PEDAL APPARATUS

Albert Sabo, Bloomsburg, Pa.

Application February 11, 1952, Serial No. 270,933

5 Claims. (Cl. 84—422)

1

This invention relates to a heel operated drum beater apparatus and has for an object to provide such an apparatus for use as an attachment in beating a trap drum or operating a symbol.

A further object of this invention is to provide a drum beater apparatus that is here operated in contrast to the conventional sole operated drum beater apparatus.

A further object of this invention is to provide a drum beater apparatus wherein the drummer may rest the sole of his foot on a stationary base portion of the apparatus and rest the heel of his foot on a pivoted depressable pedal so as to operate the beater against the drum by depressing his heel on the pedal and then return the beater to non-operative position by relieving the heel pressure on the pedal.

A further object of this invention is to provide a drum beater apparatus which is operated by the heel, thus enabling the drummer to beat the drum with much more ease due to the fact that he uses the muscles of his thigh in raising his leg and heel and then depressing it to operate the beater as contrasted with the conventional sole or toe pedal operated beater which is operated by the tendons of the shin of the leg, and thus is very tiring to the leg of the drummer. With shin operation of the pedal through the sole or toe, it is very difficult to operate the drum beater at a fast tempo, while the heel operating pedal of this invention may be operated very rapidly when needed without the extreme exhaustion that normally results from the conventional sole or toe pedal operated apparatus.

With the foregoing and other objects in view, this invention comprises the combination, construction and arrangement of parts hereinafter set forth, claimed and disclosed in the accompanying drawings, wherein:

Fig. 1 is a side elevational view, partly broken away, of the heel operated drum beater apparatus of this invention.

Fig. 2 is an end elevational view looking toward the right end of Fig. 1.

Fig. 3 is a left end partly fragmentary elevation of Fig. 1.

Fig. 4 is a fragmentary top plan view, partly in X-ray, of the heel pedal end of the apparatus.

There is shown at 9 the heel operated drum beater pedal apparatus consisting of a base 10 having one end thereof formed into a pair of spaced apart clamp fingers 11 cooperating with a clamp plate 12 which is pivoted at 13 on a

2

U-bracket 14 and operable by a thumb screw 15 for clamping the apparatus to the drum hoop of a base drum or the like in a conventional manner, cushioning pads being provided, if desired, on the different surfaces of the clamp fingers 11 and clamp plate 12.

Secured to the base 10 adjacent its clamping end is the standard 16 consisting of a pair of spaced apart upright posts. Mounted intermediate on the standard 16 is the cross-bar 17. Oscillatably pivoted through the top of the standard 16 is a cross-shaft 18 journaled in the standard 16 at 20 and provided at one end with an off-set 21. A tension spring 22 has one end 23 hooked over the cross-shaft off-set 21 and has its other end secured relative to the base 10 as by a screw 29 fastened in one of the posts of the standard 16. The tension spring 22 thus permits cross-shaft 18 to oscillate within its journals 20 but tends to restore it to the position wherein the off-set 21 is in the lowermost position.

Secured about the midpoint of the cross-shaft 18 is a beater stem mount 24, the mount 24 being fixed relative to the cross-shaft 18 by means of a suitably located set screw passing through the mount 24 into gripping action with the cross-shaft 18. The mount 24 is provided with an aperture for receiving one end 25 of the beater stem 26, the drum beater 27 being mounted at the other end thereof. The beater stem end 25 is adjustably fastened in the mount 24 by means of a set screw 28 passing through the side of the mount into gripping contact with the stem end 25. Pivotedly secured at 30 to the end of the mount 24 is an inverted wire shaped pull link 31. A pair of spaced apart triangular shaped rocker arms 32 are pivoted at an intermediate angle corners 33 to the cross-bar 17, and the lower ends of the wire shaped pull links 31 are each pivoted to the upper angle corners 34 of the rocker arms 32. The lower angle corners 35 of rocker arms 32 are each pivoted to a short leg 36 of a Z shaped lower pull link 37. The Z shaped pull link 37 has an intermediate arm 38 long enough to extend to the other end of the base 10, and has its other short leg 40 pivoted at 41 to the lower angle corner of a second pair of rocker arms 42.

The intermediate angle 43 of rocker arms 42 are pivoted to the ends of the legs 44 of a U-shaped floating shaft 45 secured at 46 for oscillatory movement adjacent on the extreme end 47 of the base 10, this end 47 of base 10 having been reduced in width by being cut away at 48 to

permit the lower pulling ends 48 and their pivotal connection 41 to be depressed below the surface of the base 10. The upper corner 50 of each rocker arm 43 is pivoted to the opposite sides of a heel pedal 51, the other end of the heel pedal 51 being pivotally secured by a hinge 52 to a sole supporting plate 53, the plate 53 being supported on the base 10 and extending forwardly to between the posts of the standard 16. Wear sheets 54 and 55 are provided on the upper surfaces of the heel pedal 51 and sole plate 53, and may be removably secured thereto by suitable screws for replacement after extreme wear has taken place.

In operation, the base 10 rests on the floor after its clamping end has been secured to the drum to be operated by means of the clamp fingers 11 and clamp plate 12 and the thumb screw 15. The beater 27 is secured in position by its set screw 28 on the beater stem end 25, it being removable for storage or shipment. The drummer merely rests the sole of his foot on the wear sheet 55 of the sole plate 53, and rests his heel on the wear plate 54 of the heel pedal 51. To operate the beater against the drum, he merely depresses his heel, causing the heel pedal 51 to pivot downwardly and as viewed in Fig. 1, causing the lower rocker arms 42 to rotate in a clock-wise direction while rotating the U-shaped shaft in a counter clock-wise direction, thus exerting a rearward and downward pull on the lower Z shaped pull links 31.

This transmits a similar downward and rearward pull on the lower ends of the forward rocker arms 32 pivoting such rocker arms about the cross-bar 17 and pulling down the Y shaped pull link 34 to thus pull down in a clock-wise direction the outer end of the drum beater mount 34 and rotate the cross-shaft 18 against the resistance of the spring 22. This oscillates the drum beater stem 28 to cause the beater 27 to strike the drum, and relieving the pressure of the heel on the heel pedal wear plate permits the spring 22 to rotate the cross-shaft 18 in the opposite direction withdrawing the beater from the drum and restoring the pedal 51 to its initial raised position ready for another operation.

With this construction, it is very easy for the drummer using his heel raised and lowered by the thigh muscles to operate the beater against the drum as fast and as often as desired without the usual extreme exhaustion of the conventional sole or toe operated drum beater pedal.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. A heel operated drum beater apparatus comprising a horizontal base, an upright standard at one end of said base, a drum beater stem mount oscillatably supported on said standard, a foot sole supporting plate fixedly mounted on said base and extending from said standard toward the opposite end of said base, a heel pedal pivotally hinged at one end to the end of said plate opposite from said standard, link means pivotally connecting the other end of said heel pedal to said drum beater stem mount to oscillate said mount in drum beating direction as said heel pedal is depressed, and yieldable means con-

nected thereto to oscillate said mount in the opposite direction and lift said heel pedal when heel pressure thereon is relieved.

2. A heel operated drum beater apparatus comprising a horizontal base, an upright standard at one end of said base, a drum beater stem mount oscillatably supported on said standard, a foot sole supporting plate fixedly mounted on said base and extending from said standard toward the opposite end of said base, a heel pedal pivotally hinged at one end to the end of said plate opposite from said standard, link means pivotally connecting the other end of said heel pedal to said drum beater stem mount to oscillate said mount in drum beating direction as said heel pedal is depressed, and yieldable means connected thereto to oscillate said mount in the opposite direction and lift said heel pedal when heel pressure thereon is relieved.

3. A heel operated drum beater pedal apparatus comprising a base, an upright standard mounted thereon adjacent one end thereof, a cross-bar intermediately mounted on said standard, a cross-shaft oscillatably mounted on said standard above said cross-bar, said cross-shaft having an off-set, a tension spring secured at one end to said cross-shaft off-set and having its other end fixed relative to said base, a beater stem mount fixed on said cross-shaft to support a beater stem and beater thereon, a pull link pivoted to said beater mount, rocker arm means intermediately pivoted to said cross-bar and pivoted at its upper end to said pull link, lower pull link means pivoted at one end to said rocker arm means at its lower end, the other end of said lower pull link means extending to the other end of said base, a second rocker arm means pivoted at one end to said other end of said lower pull link means, a shaft having an off-set means pivoted on said other end of said base, the off-set means of said shaft being pivoted to said second rocker arm means at an intermediate point thereof, and a heel pedal pivoted at its rear end to said second rocker arm means at an upper point, said heel pedal being pivotally hinged at its forward end relative to said base, the forward end of said heel pedal being spaced on said base from said standard and providing a sole receiving means on said base therebetween.

4. A heel operated drum beater pedal apparatus comprising a base, an upright standard mounted thereon adjacent one end thereof, a cross-bar intermediately mounted on said standard, a cross-shaft oscillatably mounted on said standard above said cross-bar, said cross-shaft having an off-set, a tension spring secured at one end to said cross-shaft off-set and having its other end fixed relative to said base, a beater stem mount fixed on said cross-shaft to support a beater stem and beater thereon, a pull link pivoted to said beater mount, rocker arm means intermediately pivoted to said cross-bar and pivoted at its upper end to said pull link, lower pull link means pivoted at one end to said rocker arm means at its lower end, the other end of said lower pull link means extending to the other end of said base, a second rocker arm means pivoted at one end to said other end of said lower pull link means, a U-shaped shaft pivoted on said other end of said base, the U-ends of said U-shaped shaft being pivoted to said second rocker arm means at an intermediate point thereof, and a heel pedal pivoted at its rear end to said second rocker arm means at an upper point, said heel pedal being pivotally hinged at its forward end

relative to said base, the forward end of said heel pedal being spaced on said base from said standard and providing a sole receiving means on said base therebetween.

5. A heel operated drum beater pedal apparatus comprising a base, an upright standard mounted thereon adjacent one end thereof, a cross-bar intermediately mounted on said standard, a cross-shaft oscillatably mounted on said standard above said cross-bar, said cross-shaft having an offset, a tension spring secured at one end to said cross-shaft off-set and having its other end fixed relative to said base, a beater stem mount fixed on said cross-shaft to support a beater stem and beater thereon, a pull link pivoted to said beater mount, a pair of triangular rocker arms intermediately pivoted to said cross-bar and pivoted at their upper ends to said pull link, a pair of lower pull links pivoted at one end to said rocker arms at their lower ends, the other ends of said lower pull links extending to the other end of said base, a second pair of tri-

angular rocker arms pivoted at one end to said other ends of said lower pull links, a U-shaped shaft pivoted on said other end of said base, the U-ends of said U-shaped shaft being pivoted to each said second rocker arms at an intermediate point thereof, and a heel pedal pivoted at its rear end to said second rocker arms at an upper point, said heel pedal being pivotally hinged at its forward end relative to said base, the forward end of said heel pedal being spaced on said base from said standard and providing a sole supporting means on said base therebetween.
